FORK OR SIMILAR ARTICLE OF FLATWARE

Ignacio Arcocha Basterra, La Vega s/n Guernica, Spain

Filed July 17, 1970, Ser. No. 24,645

Term of patent 14 years

Int. Cl. D7—03

U.S. Cl. D54—12

FIG. 1 FIG. 3 FIG. 2

FIG. 1 is a top plan view of a fork or similar article showing my new design;

FIG. 2 is a bottom plan view thereof;

FIG. 3 is a side elevation thereof; and

FIG. 4 is a cross-section thereof taken on line 4—4 of FIG. 1.

The design is intended for use on sets comprising spoons, forks, knives and similar articles of flatware. The essential features of my design for a fork or similar article reside in the configuration of the handle in combination with the particular type of ornamentation as applied thereto.

I claim:

The ornamental design for a fork or similar article of flatware, as shown and described.
